2 SHEETS—SHEET 2.

UNITED STATES PATENT OFFICE.

CHIPMAN J. WELLS, OF LONG BEACH, CALIFORNIA.

DISAPPEARING BED.

1,271,814.

Specification of Letters Patent.

Patented July 9, 1918.

Application filed August 26, 1916. Serial No. 117,110.

To all whom it may concern:

Be it known that I, CHIPMAN J. WELLS, a citizen of the United States, residing at Long Beach, in the county of Los Angeles 5 and State of California, have invented a new and useful Improvement in Disappearing Beds, of which the following is a specification.

My invention relates to disappearing beds 10 for use in apartment buildings and the like where economy in space is essential, and the primary object is to provide a bed which may be suspended within one of the ordinary bed compartments when not in use and 15 readily drawn out of the compartment and supported in its extended position for use.

A further object is to provide means for hanging the bed in the closet or compartment in such a manner that when it is moved 20 into or out of operating position the bed will at all times remain in a true horizontal position, thus preventing the displacement 25 of the mattress and bed clothing.

A further object is to provide means for 25 locking the bed firmly in position when extended for use and when entirely within the compartment, the locking means being automatically operated when the bed is moved to either limit of action. Other objects may 30 appear as the description progresses.

Referring to the drawings, Figure 1 is a plan of my bed and the compartment in which the same is located, partly in section. Fig. 2 is a longitudinal section of the compartment with the bed and supports shown 35 in elevation therein. Fig. 3 is a partial front elevation of the same. Fig. 4 is a transverse section of the same with the bed shown suspended to the lowest plane as indicated by 40 broken lines in Fig. 2. Fig. 5 is an enlarged section of the track and hangers for the bed. Similar characters of reference are used in the several views of the drawing and in the specification for indicating the same or similar parts.

The arrangement shown in the drawings includes a compartment 1 which is built into and comprises the space beneath the seat 2 and the closet 3 on the opposite side of the 50 central wall 4 from the seat, and in size, area and other respects is similar to the compartments usually provided for other types of disappearing beds.

A pair of angle iron tracks 5 is provided 55 in the compartment 1 which may be secured in a suitable manner to the floor 6 of the

closet 3 and the bottom 7 of the seat, or these tracks may be attached to and suspended from suitable cleats, if necessary. The tracks 5 are parallel and each track has a 60 depending flange 8 with a pair of elongated slots 9 formed therein with slightly enlarged ends 10, the forward and rear slots in each of the tracks being opposite.

The bed 11 is composed of an angle iron 65 frame 12 which is bent around to form the front and ends and the rear side is formed of a similar piece of angle iron 12' suitably secured to the member 12, the rear ends 13 of the member 12 being extended substantially beyond the member 12'. As shown in the drawings the bed 11 is arranged for sidewise movement into and out of the compartment 1 but it is obvious that this arrangement may be reversed according to 75 necessity so that a lengthwise movement of the bed may be accomplished. Suitable ends 14 are provided on the bed which may be of any desirable form or character.

When the bed is in the proper position for 80 use the frame members 12 occupy positions below the tracks 5 and each of the ends 13 of the bed frame is supported on the tracks 5 by means of angle iron bars 15 which are pivoted at opposite points on bolts or rivets 85 16 to the members 12 and the upper ends of bars 15 are provided with double flanged rollers 17 which may be inserted in the slots 9 through the enlarged portions 10 thereof so that the portions of the rollers between 90 the flanges will engage the edges of the slots. A similar pair of bars 18 are attached at their lower ends by means of the bolts or rivets 19 to the member 12 at opposite points about midway between the transverse center 95 line and the rear side of the bed. The upper ends of the forward bars 18 have rollers 20 which are similar to those on the rear bars and engage the forward slots in the tracks. The rollers 17 and 20, as shown in Fig. 5, 100 are pivotally mounted on bolts 21 which are attached to the ends of the bars 15 and 18. Longitudinally disposed connecting bars 22 are provided on each end of the bed for connecting the bars 15 and 18 at points slightly 105 below the upper ends of these bars and the upper and lower ends of the bars being equally spaced, the bars 15 and 18 will at all times be parallel, and the bed 11 which the bars support will at all times be horizontal.

The rear ends 13 of the frame member 12

are provided with a pair of outwardly extended studs 23 and 24 on each end of the bed which are suitably threaded or otherwise suitably secured to the member 12 and 5 are adapted to be engaged by the forward and rear latches 25 and 26, respectively, which are pivoted to the tracks 5 on bolts or rivets 27 and 28, respectively. The latches 25 and 26 are limited in their downward 10 movement by means of pins 29 which are adapted to be engaged by lugs 30 formed on the upper ends thereof, and the lower ends of the latches are substantially wider than the upper ends so as to provide ample 15 weight for insuring the action of the latches by gravity. Near the lower ends of the latches notches 31 are formed which are adapted to engage the pins or studs 23 and 24, and it will be observed by reference to 20 Fig. 2 that the ends 32 of the latches are slightly narrower than the portions 33 just above the notches 31 and the ends 32 are suitably curved so that when engaged by the studs 23 and 24, in the upward movement of 25 the bed 11, the latches may be raised by the studs sufficiently to permit the seating of the studs in the notches 31. It will also be observed that the forward latch 25 is normally inclined toward the rear of the compartment 1 while the rear latch is inclined in 30 the opposite direction, to correspond to the movement of the bed when it is placed in and out of operative position.

In Fig. 2 the bed is represented in full 35 lines in its extended position in readiness for use and in broken lines in its lowest position and in its innermost raised position where the bed will normally be supported when out of use. Angle iron legs 34 are 40 provided on the front side of the bed which are pivoted to the inner side of the member 12 on bolts or rivets 35 and are capable of being normally held folded against the member 12 as shown in Fig. 4, or, downwardly extended, as shown in Fig. 2, for 45 supporting the front side of the bed when the same is extended for use.

In operation, the bed being in normal 50 position in the compartment 1 and so held by means of the engagement of the stud 24 with the notch 31 in the latch 26, as shown in broken lines in Fig. 2, may be released by a slight quick rearward movement of the bed which will raise the latch 26 so that the 55 stud 24 will slide over the raised portion 33, and the bed being of greater weight than the latch and being allowed to fall of its own accord, will move the stud 24 by the notch 31 in the latch without permitting 60 the same to seat in the notch, the lower end of the latch then falling by gravity to its lowest position as determined by the pin 29 and the lug 30. The bed 11 may then be moved forwardly on the tracks 5, the rollers 65 17 and 20 on the bars 15 and 18 moving in

the slots 9 of the tracks until the ends of the slots are reached, when the bed will be suspended in the lowest forward position as indicated in Fig. 2. The bed may then be raised into the position shown in full lines 70 in this figure by a quick forward and upward movement, during which movement the studs 23 on the ends 13 of the member 12 will engage and raise the latches 25 until the highest position of the bed is attained, 75 when the studs 23 will seat in the notches 31 of the latches 25, and the bed will then be held firmly suspended on the bars 15 and 18 and the latches 25. In this position, the bed will be cantalivered outside of the compartment 1 and the rear side thereof held as described, the front side being additionally supported by means of the legs 34.

It will be understood that the bed when it is held in the position described is supported 85 against movement in a manner similar to that of a swing with the ropes or wires on each side of the seat crossed, the bars 15 and 18 preventing a further forward movement and the latches preventing a backward movement. Now, when it is desired to replace 90 the bed in its normal position within the compartment 1, the bed may be released from the latches 25 by a quick forward and upward movement, in a manner similar to 95 that in which it was released from the rear latches 26, the studs 23 being disengaged from the notches 31 in the latches and the bed falling by gravity to the lowest position shown. The bed may then be pushed backwardly into the compartment and raised 100 into the position shown in Fig. 2 when the studs 24 will be engaged by the notches 31 on the latches 26.

An opening 36 is provided in the front of 105 the compartment 1 to permit the movement of the bed 11 therethrough, and a suitable door or closure 37 may be hinged to the base 38 for closing the opening when the bed is not in use.

The bed 11 may be made of metal as 110 shown with the ordinary type of wire mattress 39 attached thereto, or any other form of bed with suitable springs may be used in lieu of that shown. In any event the weight 115 of the bed will not be sufficiently great to defeat the objects of this invention, or prevent the movement of the bed into and out of operative position. It is believed to be possible to modify the structure shown to a 120 considerable extent without enlarging the scope or departing from the spirit of my invention, and I desire to claim broadly on the principle of a suspended bed of the character described.

Having thus described my invention, what 125 I claim is:

1. A bed comprising a horizontally disposed frame pivotally and slidably supported for movement, guide means for regulat-

ing the direction of movement thereof, and locking means suspended from said guide means for sustaining said frame in position at opposite extremes of movement.

5 2. A bed of the character described comprising fixed supports positioned above the range of action of the bed, a frame carrying a bed, bars slidably and pivotally connecting said frame and supports for suspending 10 the bed therebeneath, said frame being extensible horizontally and vertically from a normal plane to a plane substantially coincident with said supports for use, and members pivotally suspended from said supports 15 for engagement with and for locking said frame at opposite extremes of action.

3. A bed of the character described comprising fixed supports, a frame having members substantially in vertical alinement 20 therewith, connections slidably and pivotally attached to said supports and pivotally attached to said frame at opposite points intermediate of the sides of said bed, additional connections from said supports 25 attached to said frame at opposite points exterior of said bed, and means depending from points above the frame for engagement therewith for supporting the same at opposite extremes of action.

30 4. A bed comprising a longitudinally and pivotally movable frame, parallel supporting means therefor capable of sustaining said frame in a true horizontal position at all times while stationary and during the 35 movement thereof, and gravity actuated locking means for locking said frame at selected points against movement.

5. A bed of the character described comprising fixed parallel supports, means depending therefrom for supporting the bed, a bed frame pivotally attached to said depending supports at opposite points intermediate of the sides and exterior of one side of said bed and latch means on said 45 fixed supports and engaging said frame for locking said bed at different extremes of movement.

6. A bed of the character described comprising fixed supports and slidably pivoted 50 supports depending therefrom, a frame normally disposed beneath said fixed supports and pivotally attached to said pivoted supports, pivoted legs on the outer side of said frame and means on said fixed supports en-

gaging said frame for supporting said bed 55 in horizontal position.

7. A bed of the character described comprising a pair of fixed parallel supports, a frame normally disposed therebeneath, members pivotally attached to said supports 60 and to said frame at opposite points for suspending the frame in operating position, means for slidably attaching said members to said supports to permit the extension of said frame from beneath said supports, and 65 means for locking said frame at desired points within its range of action.

8. A bed of the character described, comprising a pair of fixed supports, spaced members depending therefrom and pivotally and slidably held thereon, a bed frame having opposite parallel extensions from one side and disposed beneath said supports, means for suspending said frame from said depending members, said members being attached to said frame at points intermediate of the sides of and exterior of one side of said bed, and means whereby the bed when closed beneath said supports or open and extended relative thereto may 80 be supported in fixed stationary relation thereto.

9. A bed of the character described comprising fixed supports having slidably and pivotally depending members, a frame attached to and suspended on said depending members, said frame being normally closed and suspended beneath said supports and capable of extension outwardly therefrom into a horizontal plane for use, and gravity 90 actuated means for locking said frame at both extremes of action.

10. A bed of the character described comprising fixed supports provided with depending and slidably disposed hanger members, a frame supported on said hangers and extensible outwardly from said supports for use, gravity actuated members suspended in the path of said frame, and means on said frame for engagement therewith, for locking said frame in open and closed position.

Signed at Los Angeles, in the county of Los Angeles and State of California, this 10th day of August, 1916.
